H. G. Burns ATTORNEY

UNITED STATES PATENT OFFICE

JESSE M. DUNGAN, OF FORT WAYNE, INDIANA

GAS STOVE

Application filed February 14, 1927. Serial No. 167,982.

This invention relates to improvements in gas stoves of that type wherein hydrocarbon fuel is utilized. The object of the improvement is to provide means for maintaining the 5 gaseous vapor in the feed pipe for the stove in a constant state of dryness so as to be in readiness and in proper condition for combustion when admitted to the burners, and thus obviate the customary practice of priming 10 and preliminary heating of the burners.

This object is accomplished by the construction illustrated in the accompanying drawings, in which:—

Fig. 1 is a plan view of a gas stove equipped 15 with the invention; and

Fig. 2 is a detail showing an elevation of a lighter in conjunction with the feed pipe through which hydrocarbon vapor is supplied to the stove.

20 The characters appearing in the description refer to parts shown in the drawings and designated thereon by corresponding characters.

The invention is used in connection with a 25 gas stove 1 having a series of burners 2 which are respectively supplied with a mixture of gas and air through corresponding ducts 3, each having a mixer 4 and valve 5, the latter being connected with a common manifold 30 pipe 6. The construction and arrangement of the burners including their ducts, mixers, valves and the manifold pipe are such as is ordinary in the art. The invention contemplates in connection with the stove a pilot 35 lamp for igniting the gas mixture when supplied to the various burners, which igniter is of the ordinary type, and consists of a shell 7 having a series of apertures 8 and a gas burner 9 which is connected with the manifold 40 6 by a pipe 10, there being a valve 11 provided for controlling the supply of gas to the burner. The valve 11 is of the customary type for regulating the pilot lamp, and is normally open to such extent as to admit the 45 passage of sufficient gas to sustain a single jet of flame 12 from the burner 9, and may be fully opened by pressing down upon the stem 13 of said valve so that the supply of gas through the burner 9 is sufficient to cause 50 the flame 14 to be projected through each of

the openings 8 in the shell with sufficient force as to reach the corresponding burners 2, as in the ordinary practice. In this manner when gas is turned on to any one of the burners the gas mixture as it passes from the burner 55 may be ignited.

In connection with the shell 7 is arranged a supply pipe 15, the pipe having loops 16 formed therein so that the pipe passes through the shell 7 several times in the upper part 60 of the shell, so as to be exposed constantly to the flame 12 of the pilot lamp. The supply pipe 15 is provided with a regulating valve 17 and is connected with the manifold 6. Also, the supply pipe has connection with 65 a pair of drums 18 and 19 with which it has communication through the customary fixtures 20 for controlling the supply of hydrocarbon vapor from the respective drums.

The invention contemplates the use of hydrocarbon in the form of casing head gasoline or naphtha of such volatility as to vaporize at a pressure less than that of the atmosphere, so that gaseous vapor is supplied under constant pressure to the supply pipe from one 70 or the other of the drums which contain the supply of liquid fuel. The vapor thus supplied is normally of insufficient dryness as to mix readily with the air and form a completely combustible mixture. However, in the 75 present invention the vapor is dried by the heat derived from the pilot flame 12 as the vapor passes through the supply pipe from the drums to the manifold.

In utilizing the invention the pilot lamp is 80 initially heated by applying a torch momentarily so that the vapor in the supply pipe is dried. The dried vapor is then admitted through the valve 17 into the manifold and passes through the partially open valve 11 85 to the burner 9 whereupon the pilot flame is established in the shell. As the flame of the pilot lamp burns continuously the vapor in the supply pipe 15 is maintained in a constant state of dryness and in readiness to be admitted to any or all of the burners of the stove accordingly as the corresponding valves 90 5 are turned, the consequent mixture of gas and air emitted from the burners being ignited by the flame 14 that is projected from 100

the pilot lamp upon manipulation of the valve stem 13.

What I claim is:—

In apparatus of the class described, a gas stove having a series of burners spaced apart; 5 a pilot lamp; a manifold pipe having independent connections respectively with said burners and lamp; a perforated shell disposed over said lamp; a supply pipe extending through said shell over said lamp and 10 connected to said manifold; a source supplying hydrocarbon fuel to said supply pipe under pressure; and valves controlling the corresponding connections between said manifold and burners, said pipe being heated constantly by said lamp whereby the flame of 15 said lamp is continuously maintained during operation of the burners and after all the valves for said burners are closed and the burners extinguished.

20 In testimony whereof I affix my signature.

JESSE M. DUNGAN.
